UNITED STATES PATENT OFFICE.

DAVID H. WILSON, OF CHICAGO, ILLINOIS, ASSIGNOR TO ROBERT BINES,
OF CHICAGO, ILLINOIS.

TELEPHONE APPARATUS.

No. 830,272.

Specification of Letters Patent.

Patented Sept. 4, 1906.

Application filed January 2, 1906. Serial No. 294,251.

To all whom it may concern:

Be it known that I, DAVID H. WILSON, a citizen of the United States, residing at Chicago, in the county of Cook and State of Illinois, have invented a certain new and useful Improvement in Telephone Apparatus, of which the following is a specification.

This invention relates to telephone apparatus, and has for its object to provide a new and improved apparatus of this description.

The invention is illustrated in the accompanying drawing, wherein the figure is a view showing diagrammatically a construction embodying the invention.

Referring now to the figure, there is shown a transmitter A, connected in a circuit containing a source of current-supply B. This transmitter-circuit contains two coils A' B', which are connected in multiple, said coils being wrapped about the iron cores A² B². These iron cores also contain coils C C', which are connected in series and which are also connected with the main line D. Between the cores A² B² are two cores E and F, preferably magnetically insulated from the cores A² B². In this construction the ends of the cores A² and B², which are opposite each other, are unlike poles, this result being secured by the winding of the coils thereon. In other words, the cores E and F are interposed between unlike poles of the cores A² B². The cores E and F are provided with the coils E' F'. Both these coils are connected to the receiver G. It will be seen that the receiver is connected in circuit with two coils each wound upon a separate core upon which there are no other coils and that the circuit containing the receiver is electrically independent of the transmitter-circuit and the line-circuit and contains no battery or other electrical generator.

In operating the device the operator talks into the receiver at one end of the line. A talking-current is then generated in the main line D and is transmitted to the coils C C'. It energizes the cores of these coils, and because of the variation of the current the magnetism

of the core is varied. This induces a talking-current in the coils E' and F', and this current is conducted to the receiver and there reproduced into speech..

In view of the fact that the receiver-circuit and coils are electrically independent of the main line and the transmitter-circuit the speech is reproduced entirely free from the extraneous inductive effects on the line, and hence absolute clearness is secured.

I claim—

1. A telephone apparatus comprising a transmitter-circuit, two separated iron cores about which a portion of said transmitter-circuit is wound, a main line-circuit having a portion also wound about said cores, two separated iron cores interposed between said first-mentioned cores each provided with a coil, and a receiver connected in circuit with both of said coils.

2. A telephone apparatus comprising a transmitter-circuit, two separated iron cores about which a portion of said transmitter-circuit is wound, a main line-circuit having a portion also wound about said cores, the windings being such that the opposed poles of said cores are unlike, two separated iron cores interposed between said first-mentioned cores, each provided with a coil, and a receiver connected in circuit with both of said coils.

3. A telephone apparatus comprising a transmitter-circuit, two separated iron cores about which a portion of said transmitter-circuit is wound, a main line-circuit having a portion also wound about said cores, the windings being such that the opposed poles of said cores are unlike, two separated iron cores interposed between said first-mentioned cores, each provided with a coil, and a receiver connected in circuit with both of said coils, the several cores magnetically insulated from each other.

DAVID H. WILSON.
